HUGO REINZ, OF BERLIN-SPANDAU, GERMANY

PACKING MATERIAL

Application filed January 5, 1929, Serial No. 330,480, and in Germany October 3, 1928.

In order to produce a packing material (especially for the cylinder blocks of internal combustion engines operating with high compression) which will fulfill all requirements, the present invention employs a fabric of asbestos and metal of perfectly compact texture, in conjunction with an impervious material which forms a covering or sheathing for said fabric and is combined with the 10 fabric to form a homogeneous whole.

Preferably, the fabric, which has already been woven as closely as possible on the loom, is first impregnated with a heat- and moisture-resisting substance for instance a 15 phenolic condensation product such as "thiolite", which is a sulphur derivative of a condensation product of formaldehyde and phenol. The fabric thus treated is then united with the impervious material, for example, a mixture of long-staple asbestos, rubber and a suitable filler. The filler may consist of any one of a variety of suitable 20 substances, among which may be mentioned, by way of example, heavy spar, magnesia and silicon. Instead of rubber, thiolite may be used in order to render the mixture of the fibrous asbestos with the filler impervious. The union between the treated fabric and the 25 impervious material is effected by rolling the impervious layers on to both sides of the fabric under heavy pressure and with the collaboration of heat. In this way a web is produced which is flexible and capable of 30 withstanding the highest temperatures, pressures and other powerful stresses, which web can be cut by stamping without any further treatment, and can thus be brought into the desired shape for any type of packing, and particularly into the shape of the 35 usual cylinder-block packing for internal combustion engines. At the same time, the most diversified combinations of asbestos and metallic filaments can be employed in the manufacture of the fabric, such as warps of 40 metal and asbestos wefts; also asbestos-metal doubles for the warp, and on occasion, for both warp and weft; and so on.

The invention is illustrated, diagrammatically and by way of example, on the 45 accompanying drawing.

Fig. 1 represents the asbestos-metal fabric before treatment.

Figs. 2 and 3 are respectively a plan and a cross section of the fabric both on a larger scale than Fig. 1.

Fig. 4 represents a cross section of the finished fabric.

Fig. 5 shows a cylinder block packing made from the treated or finished material.

The warp threads *a* of the fabric consist of metal (preferably phosphor bronze of high strength) whilst asbestos threads *b* with a metal core serve as the weft. These threads *a* : *b* are so closely interwoven that, as shown in Figs. 2 and 3, the fabric is extremely compact and close from the outset.

The fabric is next impregnated with the previously mentioned heat- and moisture-resisting material (e. g., thiolite) which renders the fabric completely impervious, without loss of flexibility and suppleness.

The fabric so pretreated is next (Fig. 4) provided on both sides with an impermeable layer *c* of suitable character, as described above, in such a way that the impermeable material is completely forced into the texture of the fabric, so that the fabric *a* : *b* is, as it were, encased in the impermeable material on all sides. The homogeneous union of the fabric with the impermeable material is best assured by the already mentioned rolling-on of the latter under heavy pressure and with the collaboration of heat.

The web thus formed can then be stamped out in the form of cylinder-block packings A (Fig. 5) and these, after being coated with graphite, can be placed in packing position without any further treatment.

Experiments have shown that the packing according to the invention fulfills the most stringent requirements in respect of pressure, resistance to heat and indeed in all other respects, and that there is no fear of corrosion or penetration of the edges of the packing, especially at the susceptible parts *d*, notwithstanding the absence of any marginal protection means. Another advantage is that the new packing can be thinner in substance than the cylinder-block packings hitherto in use. For this reason smaller surfaces

are exposed to attack, the compression space can be correspondingly reduced, and the degree of compression therein accordingly increased, whereby the output of the engine is improved and the fuel more favourably utilized.

Despite its high content of asbestos, the packing is a heat conductor, and is distinguished by a very low loss on incineration.

- 10 In accordance with its texture, its strength is very high in all directions, that is to say, in the longitudinal and all transverse directions, due to the high tensile strength of the metal employed and due to the closeness, 15 density and compactness of the fabric. It is also to be observed that the strength of the fabric is further increased by the fibrous asbestos employed in the impervious material which constitutes an integral part of the 20 finished product.

20 I claim:—

1. A packing material composed of closely woven asbestos-metal fabric and a sheathing of impermeable material intimately united therewith to form an inseparable whole, 25 said impermeable material being constituted by a mixture of asbestos, a filler, and a binder therefor.
2. A packing material composed of closely woven asbestos-metal fabric comprising metal warp threads and asbestos weft threads impregnated with heat- and moisture-resisting substance, and a sheathing of impermeable material intimately united therewith to 35 form an inseparable whole.
3. A packing material comprising a closely woven asbestos-metal fabric comprising metal warp threads and asbestos weft threads impregnated with a heat and moisture resisting 40 product of phenolic condensation, and a sheathing of impermeable material intimately united therewith to form an inseparable whole.
4. A packing material comprising a closely woven asbestos-metal fabric impregnated 45 with a phenolic condensation product and a sheathing of impermeable material intimately united therewith to form an inseparable whole, said impermeable material being constituted by a mixture of asbestos, a filler and a binder therefor.

In testimony whereof I affix my signature.
HUGO REINZ.
